RADIATOR

Austin H. Hart, New York, N. Y.

Application January 14, 1931. Serial No. 503,580

3 Claims. (Cl. 257—124)

My invention relates to a radiator for house heating, and more particularly to the type employing fins for the conduction and radiation of heat.

5 The principal object of my invention is to cast a radiator in one piece and provide means whereby radiator fins may be easily assembled and maintained in uniform alignment.

Another object is to provide fins of either single 10 plate or corrugated sectional form which are adapted to be slipped over the top of the body portion of the radiator or secured to the sides thereof.

Another object is to have supporting legs cast 15 integrally with the radiator, each leg being provided with openings adapted to receive standard pipe fittings.

Heretofore, the practice has been to pass fins over the end of a tube or set the fins up in a 20 fixture, and force the tube through openings in the fins, then assemble end fittings over the ends of the tube. Considerable time was required to complete these operations, which increased the manufacturing cost. With my improved type of 25 radiator and fin construction, one casting is made of the body with the included leg portions or end fittings cast integrally therewith, and the fins are adapted to be assembled by placing same over the top of the body portion. The fins are maintained in a set position by means of positioning 30 grooves or slots. The entire assembly is then dipped in a galvanizing bath which seals the fins on the body portion and provides a good metallic contact between the fins and the radiator body.

35 These and other features will appear in the following description and drawing, in which:

Figure 1 shows an elevational view, with part 40 in section, of a one piece radiator assembly having fins thereon;

Fig. 2 is a vertical section taken on the line 2—2 of Fig. 1;

Fig. 3 is a perspective detail of a single plate fin having flanged edges;

Fig. 4 is a vertical section of a modified form 45 of radiator showing a plurality of central tubular or body portions cast integrally with the end members;

Fig. 5 is a side elevational view, with a part 50 broken away, of a one piece cast wall radiator assembly having fins thereon.

The radiator in general, shown in Fig. 1, comprises a body portion 10 and two leg portions 12 and 14, all cast as one integral member. A hollow interior 16 provides a communicating passage 55 from the lower end of leg 12 through the main

body structure 10 to the lower end of the other leg 14. Threaded openings 18 communicating with the passages in each of the legs are adapted to receive suitable pipe fittings or plugs. The upper edge 20 of the body portion has evenly spaced fin positioning slots 22 cut into the surface to receive fins 24.

The fins 24 are stamped from sheet metal and have a slotted lower portion 26 shaped to correspond with the shape of the body portion 10. 65

In Fig. 2, I show the body, for example, as wedge shaped, and the fin in Fig. 3 with a wedge shaped slot 26 adapted to fit over the said body portion. Inwardly disposed flanges 28 are formed at the edges of the slotted portion which provide 70 a large contacting surface area when in engagement with the body portion 10. Flanges 30 are formed on the sides of the fins to provide a flush side surface when assembled, and individual pockets for the heated air to pass through. 75

This type of fin is assembled by slipping the slotted end 26 over the body portion 10 of the radiator and forcing same downward until the flat portions 32 at the apex of each wedge shaped slot 26 engage the slots 22 in the body 10. The 80 flanges 28 converge slightly toward each other and provide a substantial grip on the sides of the body portions after assembling. When the fins are all assembled, they are maintained in a fixed position and properly spaced relation by 85 means of the gripping action of the flanges 28 and positioning slots 22.

After the assembly is completed, the entire unit is dipped in a galvanizing bath which coats the radiator with a galvanized finish and seals 90 the fins in their set position on the body portions as well as providing a good metallic contact.

In Fig. 4, I have shown a modified form of one piece cast radiator in which a double body, or 95 two tube body portion 34 is cast integrally with end leg members 36. Fins 38 are provided with two slotted openings 40, and are adapted to straddle the body 34 when assembling. Grooves 42 in each of the two tubular portions 34, position the fins in the same manner as the slots 22 previously described. More than two body portions may be provided if desired.

Fig. 5 illustrates a wall type radiator which is similar to the form previously described, with 105 the exception of the leg portions. Short stub portions 44, 46 project below each end portion, and are provided with threaded openings 48 for suitable pipe fittings.

Various changes may be made in the struc- 110

ture here shown and described as forming this invention any such changes still being within the scope of the invention here claimed, if the principles of construction and the results above described are substantially preserved.

Having described my invention, I claim:

1. In a radiator of the character described, a wedge shaped cast hollow body portion having legs cast integrally therewith, stamped fins having a wedge shaped open lower portion adapted to engage the surface of the body portion, and slots in the upper edge of said body portion adapted to have each fin inserted within same and to retain said fins in their set positions.

15

2. In a radiator of the character described, a cast hollow body portion comprising a plurality of tubular shaped sections, hollow leg portions cast integrally therewith, and fins having a plurality of slotted openings adapted to engage the tubular shaped portions.

3. A fin radiator comprising a one piece hollow radiator body having hollow legs formed integrally therewith, said legs being adapted to support the radiator in an upright position and having two tapped openings in each leg for suitable pipe connections.

AUSTIN H. HART.
